[57] **CLAIM**

The ornamental design for an adjustable directional lighting fixture or similar article, as shown and described.

DESCRIPTION

FIG. 1 is a top, front, right side perspective view of an adjustable lighting fixture showing our new design;

FIG. 2 is a front elevational view thereof;

FIG. 3 is a top plan view thereof;

FIG. 4 is a bottom plan view thereof;

FIG. 5 is a side elevational view thereof, the opposite side being a mirror image;

FIG. 6 is a top, front, left side perspective view of a second embodiment of our new design;

FIG. 7 is a front elevational view thereof;

FIG. 8 is a top plan view thereof;

FIG. 9 is a bottom plan view thereof;

FIG. 10 is a side elevational view thereof, the opposite side being a mirror image;

FIG. 11 is a front elevational view of a third embodiment of our new design, the third embodiment being identical to the second embodiment except for the configuration of the front;

FIG. 12 is a top, front, right side perspective view of a fourth embodiment of our new design;

FIG. 13 is a front elevational view thereof;

FIG. 14 is a side elevational view thereof, the opposite side being a mirror image;

FIG. 15 is a top plan view thereof;

FIG. 16 is a rear elevational view thereof;

FIG. 17 is a bottom plan view thereof.

The broken lines are shown for illustrative purposes only.
